UNITED STATES PATENT OFFICE.

JOHN NELSON, OF ROCKFORD, ILLINOIS, ASSIGNOR OF ONE-THIRD TO RALPH EMERSON AND WILLIAM A. TALCOTT, OF SAME PLACE.

KNIT FABRIC.

SPECIFICATION forming part of Letters Patent No. 243,787, dated July 5, 1881.

Application filed December 24, 1875.

To all whom it may concern:

Be it known that I, JOHN NELSON, of Rockford, in the county of Winnebago and State of Illinois, have invented a new and Improved 5 Knit Fabric, of which the following is a specification, reference being had to the accompanying drawing showing said fabric.

My invention consists in a knit fabric in which a change is made in the body of the 10 fabric from a yarn of one size or color to another of different size or color by throwing in the new yarn a short time before the other one is cut off, so that their ends overlap each other at the point where the change is made, thus 15 producing a smooth neat-looking fabric without knots or projecting ends.

In the drawing, A represents one yarn, and B the other, showing, in this instance, yarns of different sizes overlapping each other at 20 the point c, the wrong side of the fabric being shown.

A machine for producing my improved fabric is shown and described in a patent granted to me in the United States April 15, 1879, No. 214,309, to which reference is hereby made, 25 which renders further description unnecessary here.

I claim—

A knit fabric composed of yarns differing in size or color, interchanged in the fabric with 30 their ends overlapping, whereby a smooth even fabric is produced, substantially as hereinbefore set forth.

In testimony whereof I have hereunto subscribed my name.

JOHN NELSON.
